(57) **CLAIM**

The ornamental design for a front face of a vehicle wheel, as shown and described.

DESCRIPTION

FIG. 1 is a perspective view of a front face of a vehicle wheel showing my new design;

FIG. 2 is a front elevational view thereof; and,

FIG. 3 is a left side elevational view thereof.

In the drawings the broken lines depict portions of the wheel that form no part of the claimed design.
